CLAIM

I claim the ornamental design for a mixing tap, as shown and described.

DESCRIPTION

FIG. 1 is a right side view of a mixing tap showing my new design, the left side being a mirror image thereof;

FIG. 2 is a front elevation view thereof;

FIG. 3 is a top view thereof;

FIG. 4 is a front, right side perspective view thereof;

FIG. 5 is a back elevation view thereof;

FIG. 6 is a back, right side perspective view thereof; and,

FIG. 7 is a bottom view thereof.

The portions of the mixing tap shown in broken lines form no part of the claimed design.
